Primary Examiner — Ricky Pham(74) *Attorney, Agent, or Firm* — Vani Moodley, Esq.**(57) CLAIM**

The ornamental design for a fryer, as shown and described.

DESCRIPTION

FIG. 1 is a perspective view showing the front of a fryer showing our new design with its door closed.

FIG. 2 is a perspective view showing the front of the fryer with the door open.

FIG. 3 is a rear view of the fryer.

FIG. 4 is a left side view of the fryer with the door closed.

FIG. 5 is a front view of the fryer with the door closed, with a line showing the plane upon which a sectional view of FIG. 7 is taken.

FIG. 6 is a right side view of the fryer with the door closed; and,

FIG. 7 is a right sectional view through the fryer taken from top to bottom.

The broken lines shown in the drawings depict portions of the fryer that form no part of the claimed design.
